BURNER MOUNT FOR OIL BURNING
LOCOMOTIVES

Leonard K. Botteron, Omaha, Nebr.

Application October 24, 1938, Serial No. 236,770

1 Claim. (Cl. 158—3)

This invention relates to mounts for oil burners for locomotive fire pans. In such devices the oil is atomized by steam and burned in suspension in a current of air induced by the steam blast issuing from the burner.

The usual burner casting is rectangular in shape and is usually surrounded by ordinary fire brick of rectangular form (2½" x 4½" x 9"). The burner casting projects about four inches 10 into the wall from the outer side. It is difficult to fit the brick tightly around the burner casting and impossible to maintain tightness, so that the bricks soon become loosened around the casting. The resulting exposure of the casting to 15 heat leads to warping and burning.

Furthermore, a rectangular opening is not favorable to satisfactory air flow, and those which have heretofore been used are not equipped with adequate burner aligning means.

The invention provides a Venturi tube mounted 20 on the external structural elements of the fire pan and equipped with releasable means for supporting the burner and aligning it substantially on the longitudinal axis of the Venturi tube. The 25 invention also contemplates an interlock between the inner end of the Venturi tube and bricks forming a portion of the lining of the fire pan and surrounding the burner opening. This interlock is so contrived that four identical special bricks 30 of simple form may be used, the tube acting to retain the bricks and the bricks housing the end of the tube sufficiently to protect it from destructive heat.

A commercial embodiment of the invention is 35 illustrated in the accompanying drawing, in which:

Figure 1 is a vertical axial section through the Venturi tube mounted in the wall of a fire pan of conventional form except for the presence of 40 the special interlocking brick. A conventional burner is shown in elevation with its steam and oil connections, to indicate how such a burner is supported.

Fig. 2 is a perspective view of the Venturi tube 45 looking at the outer end thereof.

Fig. 3 is a perspective view on a smaller scale than Fig. 2 showing the configuration of one of the special interlocking bricks.

The plates 6, 7 and 8 are merely portions of the 50 usual sheathing of the fire pan which together with the angle 9 comprise portions of the housing and sustaining portion of the fire pan. The lower portion of the pan has a lining comprising fire bricks indicated at 11, and the vertical wall 55 through which the burner delivers its blast is lined

with fire brick of ordinary form, portions of which are indicated at 12. The opening through which the burner acts is surrounded by four identical special bricks indicated generally at 13, and shown in perspective in Fig. 3. The form of these 5 bricks can be described more readily after describing the form of the mounting tube with which they interlock.

This tube is generally indicated by the numeral 14 and flares in both directions from a narrowed portion indicated at 15. Thus, the tube may be described as a Venturi through which the burner tube 16 projects axially, the burner head 17 being inward from the throat 15 and projecting slightly beyond the inner end of the tube 14, as clearly 10 shown in Fig. 1. This tube has an external flange 18 stiffened by the webs or gussets 19 and fitting against the plate 7 around an opening formed in that plate to receive the tube. The flange has 15 bolt holes 20.

The flange 18 carries at its upper portion a boss or enlargement 21 through which a clamping screw 22 with lock nut 23 is threaded. A pad 24 beneath the clamping screw 22 serves as a seat for the burner 16 and is sustained within the 25 tube by two horizontal webs 25 and a vertical web 26. At the entrance end of the tube, and supported at a slightly lower elevation than the pad 24 is a second pad 27 which is sustained by two horizontal webs 28 and a vertical web 29. 30 The parts 24 to 29 are all cast integrally with the tube 14.

The burner tube 16 has a fuel oil supply pipe 31 and a steam supply pipe 32, and these pipes are clamped between notched retaining plates 33, one 35 above and one below and another between the pipes. The clamping force is developed by two bolts 34 which pass through the plates 33 and through the holes 35 in the pad 27. These bolts are provided with nuts 36, as clearly shown in 40 Fig. 1.

The tube 14 has at its inner end an outwardly extending flange 37 which enters but does not closely fit an annular groove 38 formed in the special bricks 13. These four bricks are 45 assembled and mate on planes which are diametrical with reference to the longitudinal axis of the tube 14, and thus form the continuous circular groove 38 which receives the flange 37 and a clearance space 39 which receives with moderate clearance the inner end of the tube 14, all as clearly shown in Fig. 1.

It will be observed, also, that the bricks 13 are so formed as to produce at 41 a flaring continuation of the opening through the tube 14, this 55

opening being further flared by the terminal bevel 42. The bricks 13 are further beveled or filleted as indicated at 43, the purpose being to avoid fragile edges at a point where close fit with the burner tube 14 is not required.

- 5 As will be readily appreciated from a consideration of Fig. 1, the structure affords a combining tube through which air is drawn from outside the fire pan by the blast action of the burner.
- 10 The fire bricks 13 provide a smooth continuation of this combining tube to the inner margin of the brick wall, and since the end of the tube 14 is housed within the ring formed by the bricks 13, it is protected from the direct action of the flame 15 which, of course, is projected inward from head 17 into the fire pan. The flange 37 interlocks with the bricks 13 and assists in holding them in place. It will be understood that the holes 20 in flange 18 receive attaching bolts which connect the 20 flange with plate 7, so that the brick lining does not sustain the tube. The pads 24 and 27 provide a convenient mounting for the burner which ensures a rigid aligning support from which the burner can be readily released and withdrawn.
- 25 The feature of using four identical special bricks reduces expense, and the interlock not only reduces the tendency for loosening to occur but also reduces the degree of exposure entailed by loosening of the bricks, should this occur. While 30 special bricks can be used with a rectangular burner tube, practical considerations not encountered where the tube is circular require the use of several different forms of special brick in

a single mount where the tube is rectangular. As a practical matter, therefore, the round opening permits the use of a single form of special brick instead of four, which would be necessary with 5 burner tubes of the prior art.

The invention provides a simple unitary structure which sustains the protecting brick around the burner, offers a satisfactory entrance duct for combustion air, and a convenient releasable mount for the burner itself. While the structure 10 of all the parts has been described in considerable detail, it will be understood that modifications within the scope of the claims are contemplated, and that the particular burner illustrated is selected merely as typical of any burner suitable 15 for use in locomotive fire pans.

What is claimed is:

The combination of a burner pan having a refractory lining composed of rectangular bricks and having an opening for the reception of a 20 burner head produced by a symmetrical rectangular assemblage of four identical bricks forming part of said wall, each brick being rectangular in face elevation and formed with a quadrant 25 cut away at one corner such quadrants forming a circular opening through such assemblage; an independently supported burner tube projecting from the outer side of said wall part way through said opening and mating at its inner side with said opening; and means for supporting and 30 aligning a burner in said tube.
